UNITED STATES PATENT OFFICE

120,854

DESIGN FOR A LADY'S SHOULDER HAND-BAG OR SIMILAR ARTICLE

Benjamin Robert Brody, New York, N. Y., assignor to Harry Rosenfeld, Inc., a corporation of New York

Application April 8, 1940, Serial No. 91,533

Term of patent 3½ years

To all whom it may concern:

Be it known that I, Benjamin Robert Brody, a citizen of the United States of America and resident of New York, in the county of Bronx and State of New York, have invented a new, original, and ornamental Design for a Lady's Shoulder Handbag or Similar Article, of which the following is a specification, reference being had to the accompanying drawings, forming a part thereof.

In the drawings:

I claim:

The ornamental design for a lady's shoulder handbag or similar article, as shown and described.

BENJAMIN ROBERT BRODY.
